SWIMMING POOL FILTER CONTROL VALVE

Peter John Snelling, Brompton Park, South Australia, Australia, assignor to Waratah Archer Pty. Limited, South Australia, Australia, a corporation of South Australia

Filed Mar. 14, 1969, Ser. No. 16,244

Term of patent 14 years

Int. Cl. D23—01

U.S. Cl. D23—38

FIG. 1.

FIG. 2.

FIG. 3.

FIG. 4.

FIG. 5.

FIG. 6.

FIG. 7

FIGS. 1, 2, 3 and 4 are side elevational views of the swimming pool filter control valve embodying my new design;

FIG. 5 is a top plan view thereof;

FIG. 6 is a bottom plan view thereof;

FIG. 7 is an enlarged bottom perspective view thereof.

I claim:

The ornamental design for a swimming pool filter control valve, as shown.
